United States Patent Office

Des. 205,995
Patented Oct. 18, 1966

205,995

ANIMAL RAKE

Lawrence A. Montecalvo, North Scituate, R.I.
(75 Manton Ave., Providence, R.I.)

Filed Oct. 23, 1965, Ser. No. 87,866

Term of patent 14 years

(Cl. D12—4)

FIG. 1

FIG. 2

FIG. 3

FIG. 4

FIG. 1 is a perspective view of an animal rake, showing my new design;

FIG. 2 is a side elevational view thereof;

FIG. 3 is a bottom plan view thereof; and

FIG. 4 is an end view thereof.

I claim:

The ornamental design for an animal rake, substantially as shown.
